CLAIM

The ornamental design for a first aid pouch, as shown and described.

DESCRIPTION

FIG. 1 is a front elevation view of a first aid pouch, showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is a front, top perspective view thereof.

The broken lines represent stitching which forms part of the claimed design.
